UNITED STATES PATENT OFFICE.

JAMES R. MOFFATT, OF CHICAGO, ILLINOIS, ASSIGNEE TO UNION SPECIAL MACHINE COMPANY, OF CHICAGO, ILLINOIS, A CORPORATION OF ILLINOIS.

SEAM FOR SEWED ARTICLES.

1,331,717.

Specification of Letters Patent. Patented Feb. 24, 1920.

Application filed February 26, 1917. Serial No. 151,037.

To all whom it may concern:

Be it known that I, JAMES R. MOFFATT, a citizen of the United States, residing at Chicago, in the county of Cook, State of Illinois, have invented certain new and useful Improvements in Seams for Sewed Articles, of which the following is a description, reference being had to the accompanying drawing, and to the figures of reference marked thereon.

The invention relates to new and useful improvements in sewed seams, and more particularly to a sewed seam having a plurality of spaced parallel needle threads joined by cross threads extending from one side of the seam to the other.

An object of the invention is to provide a seam of the above character wherein the cross threads are so disposed as to more effectively cover the fabric intermediate the side edges of the seam, and wherein the cross threads when the seam is used for uniting fabric sections are disposed so as to more effectively tie down the loose ends of the threads of the fabric sections.

In the drawings:—

Figure 1 is a plan view of a seam embodying my improvements;

Fig. 2 is a bottom plan view of the seam;

Fig. 3 is a diagrammatic view showing the fabric sections in section and the arrangement of the threads relative thereto;

Fig. 4 is a view, similar to Fig. 3, but showing the fabric sections slightly overlapped.

My improved seam is especially useful in joining fabric sections in forming what is known in the art as a flat seam. The sections of fabric to be united or joined have their edge portions abutted or slightly overlapped and the fabric sections thus arranged are joined by threads consisting of two needle threads formed into parallel rows of loops disposed on opposite sides of the center of the seam and extending through the respective fabric sections. These loops are suitably secured on the under face of the fabric sections preferably by a looper thread or threads which not only concatenate with the needle loops but extend across the center line of the seam, joining the needle thread

loops on opposite sides of the center line of the seam. On the other face of the fabric the needle threads are connected by cross threads. These cross threads are independent of each other and are formed into half-twisted loops, the strands of which cross each other at one side of the center line of the seam so as to tie down the ends of the threads of the fabric sections, and the cross threads also cross each other at the center line of the seam.

Referring more in detail to the drawings:—

I have shown my improved seam as used for joining fabric sections. The two fabric sections are indicated at F and F'. In Figs. 1, 2 and 3 of the drawings, I have shown the edge portions of the fabric sections abutted and meeting at the center line of the seam which is indicated at s. The abutted edges are joined by means of threads.

These joining threads include two needle threads, one of which is indicated at n and the other at n'. These needle threads are arranged in parallel rows of loops disposed on opposite sides of the meeting edges of the fabric sections. A third needle thread, indicated at n² may also be used, and this thread is formed into a series of loops which are parallel with the rows of loops in the needle threads n and n', and the row of loops in the needle thread n² are disposed in the center line of the seam, passing preferably between the abutted edges of the fabric sections, as clearly shown in Figs. 1, 2 and 3. All three rows of needle loops are suitably anchored on the lower face of the fabric, and when my improved seam is used for joining fabric sections these loops are preferably anchored by a looper thread, indicated at l in the drawings, which looper thread passes through all of the needle loops, locking the same and extending from one side of the seam to the other, covering the seam and tying together the abutted edges.

Upon the upper face of the fabric there are two cross threads, one of which is indicated at 1 and the other at 2. The cross thread 1 is formed alternately into half-twisted loops 1^a and 1^b. The loops 1^a are all located on the right hand side of the

seam, as viewed in Fig. 1, and these loops are each penetrated by a needle loop. Every second needle loop passes through a loop 1^a in the cross thread 1. The cross thread 2 is formed into a series of half-twisted loops 2^a and 2^b . The loops 2^a are all located on the right hand side of the center of the seam, as viewed in Fig. 1, while the loops 2^b are on the left hand side of the seam. Each of these loops is penetrated by a loop in the needle thread. The loops 2^a are penetrated by the needle loops intermediate the needle loops passing through the loops 1^a , and the loops 2^b are penetrated by the needle loops between the needle loops passing through the loops 1^b . It will thus be seen that the shank of each needle loop is encircled by the half-twisted loop formed in the cross thread.

20 The strands of the loop 1^a cross at 1^c , while the strands of the needle loop 1^b cross at 1^d . The strands of the loop 2^a cross at 2^c , and the strands of the loop 2^b cross at 2^d . It will be noted that these crossings of the strands of the half-twisted loops are at one side of the center line of the seam, the crossings 1^c and 2^c being on the right of the center line of the seam, while the crossings 1^d and 2^d being on the left of the center of the seam. It will also be noted that the cross threads 1 and 2 cross each other at 3, that is, at the center of the seam. The needle thread n^2 lies over the crossing of the threads at 3, and the successive loops in the needle thread n^2 pass between the successive crossings in the cross threads 1 and 2.

It is well understood that when the edge portions of fabric are trimmed preparatory to uniting the same, the cutting of the fabric sections leaves loose ends of threads. When the fabric sections are united to form a flat seam by threads without interfolding of the fabric sections, these loose ends of threads often protrude through the covering threads and form an objectionable seam. One of the purposes of the present invention is to form a more effective covering for the loose ends of threads in the fabric sections. It will be noted that the strands of the half-twisted loops in the cross threads cross each other at points away from the center line of the seam, and these crossings of the threads cause the joining threads to overlie, tie down, and effectively cover all the loose ends in the threads of the fabric sections. The joining threads also cross at the center line of the seam and again serve to tie down these loose ends of the threads. My arrangement of the cross threads on the upper face of the fabric, therefore, forms a very effective covering, tying down, as above noted, all the loose ends of the threads in the fabric sections.

In Fig. 4 of the drawings, I have shown the fabric sections F and F' slightly over-

lapped, and the center line of needle loops in the needle thread n^2 passing through the overlapped portions of the fabric sections. Here again, the half-twisted loops form a very effective covering for the non-selvage or cut edge of the fabric sections, tying down the loose ends thereof.

While I have described my invention as particularly useful in connection with the joining of fabric sections, it will be understood that from certain aspects of the invention, it may be used for other purposes, as, for example, the ornamentation of fabric surfaces and the like.

Having thus described the invention, what is claimed as new is:—

1. A seam for sewed articles comprising fabric sections, means for joining said fabric sections including three parallel rows of needle thread loops, the outer rows being disposed at opposite sides of the edges of the fabric sections, while the middle row is disposed midway between said outer rows of needle loops, a looper thread joining all the needle loops at one face of the fabric sections and extending from one side of the seam to the other, cross threads joining the outer rows of needle thread loops on the other face of the fabric sections, said cross threads being disposed so as to cross each other underneath the middle needle thread and between the loops therein and each cross thread at each side of the seam, being formed into half-twisted loops disposed so that the strands of each loop cross each other between the middle row of needle loops and an outer row of needle loops.

2. A seam for sewed articles comprising fabric sections, and means for joining said fabric sections including needle threads arranged in parallel rows of loops disposed on opposite sides of the center line of the seam and extending respectively through the fabric sections, means for securing the needle loops and joining the same on one face of the fabric sections, and cross threads joining the needle threads on the other face of the fabric sections, said cross threads at each side of the seam being formed into half-twisted loops disposed so that the strands of each loop cross each other at points away from the center line of the seam whereby the cut ends of the threads of the fabric sections are tied down, said cross threads crossing each other substantially at the center line of the seam.

3. A seam for sewed articles comprising a fabric, needle threads arranged in three parallel rows of loops, which loops extend through the fabric, means for securing the needle loops on one face of the fabric, and cross threads joining the outer rows of needle thread loops on the other face of the fabric, said cross threads being formed into half-twisted loops disposed so that there is

a half-twisted loop extending about the shank of each needle loop in the outer rows of needle loops, the strands of each half-twisted loop crossing each other between the outer rows of needle loops and the center row of needle loops, said cross threads extending under the center needle thread between successive needle loops formed

therein and crossing each other underneath said center thread.

In testimony whereof I affix my signature in the presence of two witnesses.

JAMES R. MOFFATT.
